UNITED STATES PATENT OFFICE

EVERETT W. SWARTWOUT, OF WHITE PLAINS, NEW YORK.

REGENERATOR ENGINE.

Application filed September 1, 1921. Serial No. 497,763.

This invention relates to regenerator steam engines.

An object of this invention is to provide regenerator means for uniflow and turbine steam engine plants whereby the heat losses due to conduction and radiation are absorbed by the feed water and the heat energy thus conserved utilized in improving the efficiency of the plant.

10 A further feature of the invention is the provision of suitable passage means for the feed water through regions of continuously increasing temperature to effectively absorb the heat units which would otherwise be 15 dissipated and to increase the over-all efficiency of the plant.

In accordance with the more preferred forms of the invention, as applied to a uniflow steam engine, the feed water is conducted from the condenser or other source 20 of water supply through suitable passage means in heated relation with the interior of the engine cylinder through regions of continuously increasing temperature, thence 25 to the region of maximum temperature at the heads of the engine cylinder, and thence either directly to the boiler or in heated relation with the steam piping conveying the live steam from the boiler to the inlet ports 30 of the engine cylinder.

Heretofore, regeneration of the feed water has been carried out in connection with power plants embodying multiple stage heating, as in multiple expansion units such as 35 triple and quadruple expansion steam engines. In such arrangements, the feed water is heated between the respective stages of expansion and the steam in the respective cylinders enters at its highest temperature for the particular stage of the cycle and is exhausted at its lowest temperature at 40 the location of entry in the respective cylinders. Pursuant to my invention, the feed water is elevated in temperature in increments and progressively from the lowest 45 temperature of the cycle to the highest temperature and is practically applicable to such forms of steam engine power units in which the flow of steam from its entry into 50 the unit to its exhaust from the unit is in one direction solely, as in uniflow and turbine engines.

Further features and objects of the invention, will be more fully understood from the 55 following detail description and the accompanying drawings, in which

Fig. 1 is a side elevation, partly in section, of the cylinder of a uniflow engine, its exhaust collecting means and its feed water pump;

60 Fig. 2 shows a detail central vertical section of a modified form of water coil about the engine cylinder;

Fig. 3 is a similar detail central vertical 65 sectional view of a further modification of water coil;

Fig. 4 is a side elevation of the complete uniflow engine shown in Fig. 1;

Fig. 5 is a detail elevation, partly broken 70 away in vertical sectional view, of a modification of my invention as applied to a uniflow engine,

Fig. 6 is a sectional view on line 6—6 of Fig. 5; and

Fig. 7 is a further modification showing 75 the invention applied to a multi-stage turbine.

Referring to Figs. 1 and 4, the uniflow engine comprises the cylinder 1 having the oppositely disposed heads 2, 2^a. The piston 3 is of the usual type and its rod 4 is connected to the cross-head 5, mounted in the cross-head slides 5^a, of the engine frame. The connecting rod 6 extends from the cross-head 5 to the crank shaft 6^a, on which the fly wheel 7 is mounted. The control of the inlet valves may be effected, as indicated, by means of the centrifugal governor 8 and a suitable eccentric mounted on the engine shaft in the usual manner.

90 The boiler is indicated at 11 and is connected by the live steam piping 12 to the inlet pipe 13, provided with the throttle valve 13^a leading to the branch pipes 14, 15, to convey the live steam to the respective 95 inlet valves 16, 17, such as of the Corliss type.

The exhaust belt, indicated at 18, communicates with the interior of the cylinder through the exhaust ports 19, and discharges 100 through the piping 20 into a suitable exhaust collecting means such as the hot well or sump indicated diagrammatically at 21.

The cold water supply is indicated by the piping 22 provided with the usual regulating valve 23.

105 The water 24 of the hot well is drawn through the pipe 25 by the pump 26 and forced through the piping 27 to the pair of coils 28, 29, respectively encircling the work regions 30, 31, of the engine cylinder 1.

110 The outlet of the coil 28 is indicated at 32

and connects through the pipe 33 with the compartment 34 within the hollow, frame end head 2 of the engine cylinder. Such compartment 34 is annular in general formation and also encloses the steam inlet pipe 14^a leading from the branch pipe 14 to the inlet valve 16.

In similar manner, the coil 29 communicates at its outlet 35 through the pipe 36 with the compartment 37 of the right-hand head 2 of the engine cylinder.

The water from the left-hand compartment 34 flows through the discharge pipe 38 and the water from the right-hand compartment 37 through the pipe 39 into the piping 40 to the boiler 11.

Preferably, as indicated in Figs. 1 and 4, the live steam piping 12 flows into the receiver 41 prior to entry into the inlet pipe 13 of the engine cylinder; and preferably the discharge piping 40 for the preheated water passes through the receiver 41 by means of the coil 42 in heated relation with the steam 25 in the receiver and thence through the remainder of the pipe 40 into the boiler 11.

In the aforesaid stages of conduction of the feed water from the hot well or sump 21 the feed water is progressed through the several regions of continuously increasing temperature. In such progress of the feed water, the heat units absorbed by the feed water at the respective stages increases the over-all efficiency of the plant by returning 35 heat energy to the boiler and thus saves the consumption of additional coal otherwise necessary.

Such beneficial action is also derived by the flow of the feed water through the chambers 34, 37 in the respective heads 2, 2^a, of the engine cylinder, whereby the feed water is brought in close adjacency to each clearance proper within the cylinder adjacent the respective heads, and also brought in contact 45 with the inlet passages through which the live steam enters through the inlet ports of the respective heads.

In Fig. 2 I have shown a modified form 50 where the feed water piping is in contact with the cylindrical wall of the engine cylinder. In Fig. 2 the cylinder liner or wall proper of the engine cylinder is indicated at 1 and the piping is in the form of a semi-circular pipe of cast iron or similar material indicated at 60, the flat diametrical face 61 of which is brought spirally in contact with the outer face of the cylindrical wall 1 of the engine cylinder.

In Fig. 3 I have shown a further modification 65 of passage means for the feed water for the regions encircling the engine cylinder, namely, in the form of housings 65, 65^a, of rectangular passage sections arranged spirally about the cylinder liner and also compri-

ing a piping section 66, encircling the discharge pipe 20 of the exhaust belt 18. In such form of the invention, the feed water flows initially through the spiral passage of the section 66, thence through the respective openings 67, 68, into the spiral passages of the respective annular housings 65, 65^a, surrounding the working areas of the piston 3 within the cylinder 1, corresponding similarly to the arrangement shown in Figs. 1 75 and 4 as aforesaid.

Such oppositely spiralled housings 65, 65^a, are formed to fit over the respective halves of the cylinder 1 from each end to the enlargement at the exhaust belt at the center of the cylinder and bolted at their abutting faces and at other locations to seal the castings 65, 65^a about the cylinder wall.

Such spiralled housings 65, 65^a may be shrunk on the cylinder casing to effect the water seal or may be welded thereto. In certain sizes of engine cylinders, the cylinder liner and the exterior housings 65, 65^a may be cast integrally as will be understood.

If desired, the feed water may be conducted through the respective heads 2, 2^a of the engine cylinder by means of a coil, such as the flat spiral coil 70 shown in Figs. 5 and 6.

In such case, the discharge pipe 36 of the aforesaid right-hand coil 29, encircling the right-hand working area of the engine cylinder 1, connects with the inlet 71 of the right-hand spiral coil 70, disposed in the compartment 37 of the right-hand head 2^a. In similar manner, the outlet 33, of the left-hand coil 28 about the engine cylinder, connects with a spiral coil 70^a corresponding generally to the spiral coil 70, but having a clearance at its center, extending about the opening 73 in the left-hand head 2 through which the piston rod 4 extends.

Such passage means for the feed water about the engine cylinder are covered on the exterior by asbestos or magnesia as is indicated at 10 in Fig. 1 to prevent dissipation of heat energy, and the piping about the other portions of the engine cylinder which is exposed to exterior radiation, is similarly protected.

The invention is applicable for attachment to installed engines, to convert the same into regenerator engines embodying my invention, as well as for engines initially constructed to embody my invention.

Preferably, as indicated in Fig. 1, the feed water outlet pipe 40, extending longitudinally of the engine cylinder, is provided with expansion joints 75, 76, corresponding to the expansion joints 77, 78 in the steam inlet piping of the engine.

In a similar manner, the principle of my invention is utilizable for steam turbines, and I have indicated in Fig. 7 at 80 the high pressure stage, at 81 the intermediate pres-

sure stage and at 82 the low pressure stage of a multi-stage rotary steam turbine, whose driving shaft is indicated at 83. The condenser is indicated at 84 and the water pump 6 at 85. The air exhausting pump is indicated at 85^a.

The feed water is forced by the pump 85 through the piping 86 spirally encircling within the casing 82 of the low pressure stage, thence through spiral piping encircling the casing 81 of the intermediate stage, thence through spiral piping encircling the casing 80 of the high pressure stage and thence eventually through the pipe 87 to the 15 boiler.

From the above it will appear that my invention provides for progressive reheating of the feed water from the lowest temperature of the cycle of the power unit to the highest 20 temperature as desired, and such heating is carried out in increments effected substantially continuously, thereby providing for a regeneration through an infinite number of heating stages. It will also be apparent 25 that the rise in temperature of the feed water takes place at locations in the power unit where the temperature gradients are substantially uniformly maintained and in a direction counter to the drop of temperature of the steam in the working strokes. Accordingly, my invention is particularly 30 applicable to those forms of power units in which the direction of flow of the steam in the working strokes is in one direction only, 35 as in uniflow types of steam engines and steam turbines.

Whereas I have described my invention by reference to specific forms thereof, it will be understood that many changes and modifications 40 may be made without departing from the spirit of the invention, as defined by the appended claims.

I claim.

1. The combination of steam supply 45 means, a steam operated unit having entry and exhaust means for the steam, and in which the flow of the steam from the entry means to the exhaust means is in one direction, means for collecting the exhaust steam 50 in liquid form, means for conducting the collected liquid exhaust fluid in heated relation with and externally of said unit and in a direction counter to the flow of the steam through said unit, and means for conducting the thereby heated collected liquid 55 exhaust fluid to said steam supply means.

2. The combination of steam supply 60 means, a uniflow engine including a cylinder provided with oppositely disposed inlet valves and a centrally disposed exhaust port, and further provided with exhaust collecting 65 means, passage means disposed about said cylinder and extending in directions from said exhaust ports to said inlet ports respectively, means for connecting said pas-

sage means with said exhaust collecting means, and means connecting said passage means with said steam supply means.

3. The invention with a boiler of a uniflow 70 engine having two inlet portions and a central exhaust portion, said uniflow engine including a piston and having an exhaust collecting means, passage means for conducting the exhaust fluid from said exhaust collecting means in heated relation 75 with the cylinder of the engine in directions from the exhaust portion respectively toward the two inlet portions, to thereby conduct the exhaust fluid through said passage means in directions respectively 80 counter to the working structures of the piston, and means for connecting said passage means with said boiler.

4. The combination of steam supply 85 means, a steam operated unit having inlet and exhaust ports and in which unit the flow of the steam from the inlet port to the exhaust port is in one direction only, said unit further including a movable steam actuated member, means for collecting the 90 exhaust fluid from said unit, means for conducting the exhaust fluid in heated relation with and externally of said unit and in a direction counter to the working stroke of 95 said steam actuated member, and means for conducting the thereby heated exhaust fluid to said steam supply means.

5. The combination with steam supply 100 means of a steam turbine unit having inlet and exhaust means and further including a movable member actuated by the steam, exhaust collecting means for said unit, means for conducting the exhaust fluid in heated 105 relation with and externally of said unit and in a direction counter to the flow of steam through said unit, said unit further including a hollow head, means connecting said passage means with the interior of said hollow head, and means for connecting said 110 passage means with said steam supply means.

6. The combination with a steam supply, 115 of a steam operated unit having inlet and exhaust means, said unit further including a movable, steam actuated member, the flow of the steam from said inlet means to said exhaust means being in one direction only, said unit further including hollow heads at the respective ends of said unit, exhaust collecting means for said unit and means for 120 conducting the exhaust fluid in heated relation with and externally of said unit and in a direction counter to the flow of the steam through said unit, thence within the interior of said heads respectively, and thereafter to the said steam supply.

7. The combination with a steam supply, 125 of a steam operated unit having entry and exhaust means for the steam and in which the flow of the steam from the entry means 130

to the exhaust means is solely in one direction; exhaust collecting means for said unit, means for conducting the exhaust fluid in heated relation with and externally of said unit and in a direction counter to the flow of the steam through said unit, and means for conducting the thereby heated exhaust fluid to said entry means of said steam operated unit.

10 8. The combination with a steam supply of a uniflow engine having two inlet ports and a central exhaust port, said uniflow en-

gine including a piston; means for collecting the exhaust fluid; passage means for conducting the exhaust fluid in heated relation 15 with the cylinder of the engine from the exhaust port respectively towards the two inlet ports in directions respectively counter to the working strokes of said piston, and means connecting said passage means with 20 the steam supply of the uniflow engine.

In testimony whereof I have signed this specification this 31st day of August, 1921.

EVERETT W. SWARTWOUT.
